AUTO PNEUMATIC ACTION CO., OF NEW YORK, N. Y., A CORPORATION OF NEW
YORK.

PUMP-OPERATING MEANS FOR MUSICAL INSTRUMENTS.

1,118,476.

Specification of Letters Patent. Patented Nov. 24, 1914.

Application filed July 6, 1909. Serial No. 506,028.

To all whom it may concern:

Be it known that I, THOMAS DANQUARD, a citizen of the United States, residing at New York, in the county of New York and State of New York, have invented a new and useful Pump-Operating Means for Musical Instruments, of which the following is a specification.

This invention relates to operating mechanism for the pneumatic pumps or exhaust bellows of a pneumatic player, player piano, or the like.

The principal objects of the invention are to provide operating means of such character that the exhaust feeders or pumps can be operated either by foot pedals or an electric motor, each working entirely independent of the other; to provide a simple shifting arrangement handy for the operator for making the change from one to the other; to provide means connected with the motor for operating the exhaust feeders in such a manner that each of the feeders will commence to be expanded before the other has completed its expansive operation, so that the tension or pressure on the motor will be equalized to some extent during the revolution of the motor shaft; and to provide means whereby the power at the beginning of the expansion stroke will be at the maximum and will gradually decrease during the stroke whereby the natural tendency in the opposite direction will be counteracted.

The invention also involves certain improvements in construction.

Further objects and advantages of the invention will appear hereinafter.

Reference is to be had to the accompanying drawings in which—

Figure 1 is a front view of a portion of a pneumatic musical instrument showing a preferred form of the present invention applied thereto; Fig. 2 is a sectional view of the same on the line 2—2 of Fig. 1 showing one of the exhaust feeders and mechanism for operating it; Fig. 3 is a similar view of a portion of the parts shown in Fig. 2 in a different position; Fig. 4 is a similar view with the parts in another position; Fig. 5 is a sectional view of a portion of the mechanism on the line 5—5 of Fig. 2; and Fig. 6 is an enlarged view of the operating cam.

The invention is shown as applied to a pneumatic musical instrument having a casing 10, key-bed 11, bottom rail 12, and a pair of exhaust feeders or pumps 13. The exhaust feeders are connected as usual with the main wind-trunk or brace 14. For the purpose of operating the feeders from an electric motor 15 the latter is located at a convenient position in the casing, and drives a main or motor shaft 16 mounted in fixed bearings preferably located above the main wind-trunk. On this shaft are located two operating cams 17, one for each of the pumps. The construction and form of these cams will be described hereinafter. Each one is in such position as to be able to operate a roll 18 on a pump-operating lever 19. This lever is movably supported by a link 20 to which this lever is pivoted near the center thereof and which depends from a support 21 above. With this construction the lever is capable of swinging bodily toward and from the main wind-trunk 14. The lower end of the lever 19 is shown as engaging a roll 22 on an arm 23 which is fixed on the bottom of the movable leaf of the pump which is to be operated by that lever.

In order that the cam may operate the operating lever 19 so as to effect the actuation of the movable leaf of the bellows, a fulcrum must be provided preferably between the rollers 18 and 22. For the purpose of providing this fulcrum in a movable form the following mechanism is shown. Fixed on the main wind trunk or elsewhere is a bracket 25 shown double so that it is provided with a passage through which the lever 19 passes. Pivotal mounted on this bracket or brackets is a lever 26 shown as having a roll 27 on the inner end thereof and capable of being moved into the position shown in Figs. 2 and 3 in which it engages the lever 19 and serves as a fulcrum therefor. Mounted under the key-bed is a shift lever handle 30 in convenient position for the operator and secured on a rod 31 which is adapted to turn and which has an arm 32 thereon for operating a link 33 connected with the lever 26. Turning this handle the lever 26 can be turned up to the position shown in Fig. 4 so as to permit a spring 35 to force the lever 19 out of the

path of the cam 17 so that the rotation of the cam will be inoperative to move the lever. It is also to be noticed that the spring 35 holds the lever 19 against its fulcrum when the lever 26 is down so that the motion of the lever will be steady and accurate, and at the same time tends to swing the lever around its pivot so as to keep the lower end thereof in yielding contact with the roll 22 even independently of the action which the cam 17 has for the same purpose when on its low operating side.

There are two difficulties in the way of operating musical instrument motors or feeders by constantly rotating motor shafts. One is that the tension or pressure on the motor will be very uneven as it is taxed twice to its maximum capacity on each revolution of the shaft and it twice arrives at a point where only minimum power is required. To obviate this the cam 17 instead of being a regular eccentric or ellipse is of an irregular form and has a rather sudden maximum rise 37 which gradually decreases during more than half of the circumference of the cam, and the two cams which operate the two feeders are so set on the shaft that the rises 37 are on opposite sides of the shaft so that each commences to expand its feeder before the other cam has ceased its expansive action on the other feeder. In other words, there will always be an expansive action on one feeder or the other and twice during each revolution both will be expanding, although one of them with very little force. The other disadvantage to be overcome is that while exhausting air by a bellows having flexible sides folded inward, as is usually the case, the folds lie nearly flat against the walls of the two leaves of the bellows at the beginning of the movement, and this position gradually changes until at the end of the movement they are nearly at right angles to the walls. Consequently they afford very little resistance to the atmospheric pressure at first and very much at the end of the stroke, and the power required to keep the exhaust at a certain even tension varies in the same way. It is to obviate this that the abrupt rise 37 is provided at the beginning of the stroke and the gradually diminishing rise throughout the remainder. On account of this construction the lever 19 moves faster at the beginning of the stroke and slower toward the end so as to equalize the power required throughout the stroke. The cam shown in Fig. 6 is designed for accomplishing these results and comparison of the outline thereof with the dotted line circle will show how the cam can be designed for these purposes.

In order to make room for the motor 15 at the side the feeders or pumps 13 are shown in Fig. 1 as being brought closer to-

gether than is usually the custom. In order to accommodate this construction and in fact any construction in which the feeders are contracted for any reason, the pedals are so formed that they fold up in front of the pumps. The construction of the pedal mechanism for this purpose forms the subject matter of my co-pending application filed on even date herewith entitled "folding-pedals," Patent Number 1,008,310 granted Nov. 14, 1911 and reference is to be had thereto for a specific description thereof, but it may be remarked that in the form shown the pedal 40 is connected with a link 41 connected with the movable leaf of the bellows by two pivoted links 42 and 43 which on account of being pivoted together permit the pedal to be folded up in front of the bellows as stated above.

While I have illustrated and described a preferred embodiment of the invention, I am aware that many modifications can be made therein by any person skilled in the art without departing from the scope of the invention as expressed in the claims. Therefore, I do not wish to be limited to all the details of construction shown and described, but—

What I do claim is:—

1. In a device of the character described, the combination with the pumps, pedals, and a motor for operating the pumps, of manually operated means for disconnecting the motor from the pumps so that they can be operated by the pedals; said means comprising a bracket, a lever pivoted thereon and means for moving the lever to two positions in one of which it causes the motor to be operatively connected with the pumps.

2. In a device of the character described, the combination with a pneumatic pump, pedals, and a motor, of a motor shaft, a lever adapted to operate the pump when it swings on its pivot, means on said motor shaft for operating the lever, said lever being movable out of engagement with said means, and means for positively moving said lever into operative engagement with said operating means.

3. In a device of the character described, the combination with a pneumatic pump, pedals, and a motor, of a motor shaft, a lever adapted to operate the pump when it swings on its pivot, means on said motor shaft for operating the lever, a spring for yieldingly forcing said lever away from said operating means on the shaft, said lever being movable out of engagement with said means, and means for positively moving said lever into operative engagement with said operating means.

4. In a device of the character described, the combination with a pneumatic pump, pedals, and a motor, of a lever for operating the pump, means connected with the

motor for operating the lever, yielding means for normally disengaging the lever from said operating means, and manually controlled means for causing said lever to be placed in operative engagement with the lever operating means.

5. In a device of the character described, the combination with a pneumatic pump, and a motor having a shaft, of a bracket, a lever fulcrumed on said bracket, a cam on the motor shaft, said lever engaging the pump and the cam, whereby the rotation of the cam will operate the pump, and means whereby the position of the fulcrum of said lever can be changed to a position in which the lever can move out of engagement with the cam or pump.

6. In a device of the character described, the combination with a pneumatic pump, and a motor having a shaft, of a bracket, a lever fulcrumed on said bracket, a cam on the motor shaft, said lever engaging the pump and the cam, whereby the rotation of the cam will operate the pump, means whereby the position of the fulcrum of said lever can be changed and the lever can move out of engagement with the cam, and a manually controlled handle for operating said fulcrum changing means.

30 7. In a device of the character described, the combination with a pneumatic pump, and a pedal connected therewith for operating it, of a bracket, a lever fulcrumed on said bracket, and having engagement with the pump, whereby when the lever is turned in one direction the pump will be expanded, a motor shaft, a cam on the shaft adapted to engage the lever to turn it, and a second lever pivoted on said bracket beyond the first named lever and adapted to swing into a position between its pivot and the first named lever, whereby the end of said second lever will act as the fulcrum of the first named lever.

45 8. In a device of the character described, the combination with a pneumatic pump, and a pedal connected therewith for operating it, of a bracket, a lever fulcrumed on said bracket, and having engagement with the pump, whereby when the lever is turned in one direction the pump will be expanded, a motor shaft, a cam on the shaft adapted to engage the lever to turn it, a second lever pivoted on said bracket beyond the first named lever and adapted to swing into a position between its pivot and the first named lever, whereby the end of said second lever will act as the fulcrum of the first named lever, and the first named lever will be forced into operative engagement with the cam, and means for swinging the second lever out of the way of the first named lever, so that the latter will no longer be forced into operative engagement with the cam.

9. In a device of the character described, the combination with a pneumatic pump, and a pedal connected therewith for operating it, of a bracket, a lever fulcrumed on said bracket and having engagement with the pump, whereby when the lever is turned in one direction the pump will be expanded, a motor shaft, a cam on the shaft adapted to engage the lever to turn it, a second lever pivoted on said bracket beyond the first named lever and adapted to swing into a position between its pivot and the first named lever, whereby the end of the second lever will act as the fulcrum of the first named lever, and the first named lever will be forced into operative engagement with the cam, a spring for normally forcing the first named lever away from the cam, and means for moving the second lever to permit the spring to act.

35 10. In a device of the character described, the combination with a pneumatic pump, of a bracket, a lever fulcrumed on said bracket and adapted to operatively engage the movable leaf of the pump, a pivoted link connected with said lever for supporting it, a movable fulcrum carried by said bracket for the lever, a rotary cam adapted to engage and operate the lever when the fulcrum is in a certain position, and means for moving the lever out of the path of the cam when the fulcrum is out of said certain position.

11. In a device of the character described, the combination with a pneumatic pump, of a lever for operating the pump, means for supporting the lever and permitting it to move to and fro bodily, a movable fulcrum for the lever, an operating cam adapted to engage and operate the lever, and means for moving the fulcrum to permit the lever to be moved out of the path of the cam.

12. In a device of the character described, the combination with a pneumatic pump, of a lever for operating the pump, means for supporting the lever and permitting it to move to and fro bodily, a movable fulcrum for the lever, an operating cam adapted to engage and operate the lever, and means for moving the fulcrum to permit the lever to be moved out of the path of the cam, said cam having means whereby the lever will be positively actuated in a direction to expand the pump during more than half of a revolution of the cam.

120 13. In a device of the character described, the combination with an exhaust bellows or pump, and a pedal connected therewith for operating it, of a lever adapted to swing on a fulcrum and in position to operate the bellows when it swings, a motor for operating said lever, and movable means adjacent to the lever for rendering said lever inoperative to transmit motion from the motor to the pump.

14. In a device of the character described,

the combination with an exhaust bellows or pump, and a pedal connected therewith for operating it, of a lever adapted to swing on a fulcrum and in position to operate the bellows when it swings, a motor for operating said lever, and means for removing the fulcrum whereby the lever will be rendered inoperative.

In testimony whereof I have hereunto set my hand, in the presence of two subscribing 10 witnesses.

THOMAS DANQUARD.
